UNITED STATES PATENT OFFICE

CHARLES NESSLER, OF PALISADES, NEW YORK

DESIGN FOR A COMBINED FILAMENT STRETCHING AND TIMING ARTICLE

Application filed May 13, 1929. Serial No. 31,203. Term of patent 14 years.

To all whom it may concern:

Be it known that I, CHARLES NESSLER, a citizen of the United States, residing at Palisades, Rockland County, State of New York, have invented a new, original, and ornamental Design for Combined Filament Stretching and Timing Article, of which the following is a specification, reference being had to the accompanying drawing, forming part thereof.

Figure 1 is a front elevation of a combined filament stretching and timing article, showing my new design and Figure 2, is a side elevation of the same, on a reduced scale.

I claim:

The ornamental design for a combined filament stretching and timing article, as shown.

CHARLES NESSLER.
